DESIGN FOR A PAVEMENT SIGNAL

William E. Grace, Dallas, Tex.

Application January 2, 1934, Serial No. 50,284

Term of patent 7 years

to all whom it may concern:

Be it known that I, WILLIAM E. GRACE, a citizen of the United States, residing at Dallas, in the County of Dallas and State of Texas, have invented a new, original, and ornamental Design for Pavement Signals, of which the following is a specification, reference being had to the accompanying drawing, forming a part thereof.

Figure 1 is a perspective view, and Figure 2 is a plan view of a pavement signal, showing my new design.

I claim:

The ornamental design for a pavement signal as shown.

WILLIAM E. GRACE.
